UNITED STATES PATENT OFFICE

168,257

REFRIGERATOR CABINET

Montgomery Ferar, Detroit, Mich., assignor to
Seeger Refrigerator Company, St. Paul, Minn.,
a corporation of Minnesota

Application July 18, 1952, Serial No. 20,677

Term of patent 3½ years

(Cl. D67—3)

To all whom it may concern:

Be it known that I, Montgomery Ferar, a citizen of the United States of America, residing at Detroit, in the county of Wayne, State of Michigan, have invented a new, original, and ornamental Design for a Refrigerator Cabinet, of which the following is a specification, reference being had to the accompanying drawing, forming a part thereof.

Fig. 1 is a front perspective view of a refrigerator cabinet embodying my new design.

Fig. 2 is a side elevational view thereof.

Fig. 3 is a top plan view thereof.

I claim:

The ornamental design for a refrigerator cabinet, as shown.

MONTGOMERY FERAR.
